UNITED STATES PATENT OFFICE.

DANIEL C. RIPLEY AND CHARLES E. SCHMUNK, OF PITTSBURG, PENNSYLVANIA,
ASSIGNORS TO RIPLEY & COMPANY, OF PITTSBURG, PENNSYLVANIA, A COR-
PORATION OF WEST VIRGINIA.

DESIGN FOR A JAR.

41,002.

Specification for Design.

Patented Nov. 29, 1910.

Application filed September 15, 1910. Serial No. 582,255. Term of patent 7 years.

To all whom it may concern:

Be it known that we, DANIEL C. RIPLEY and CHARLES E. SCHMUNK, of Pittsburgh, in the county of Allegheny and State of Pennsylvania, have invented a new, original, and ornamental Design for Jars, of which the following is a specification, reference being had to the accompanying drawings, forming part thereof.

The figure is an elevation of a jar embodying our new design.

We claim:

The ornamental design for a jar as shown. In testimony whereof, we have hereunto set our hands.

DANIEL C. RIPLEY.
CHAS. E. SCHMUNK.

Witnesses:

W. P. CLARK,
J. S. BRYNER.
